BRAKE

Ludger E. La Brie, South Bend, Ind., assignor to
 Bendix Aviation Corporation, South Bend, Ind.,
 a corporation of Delaware

Application September 12, 1935, Serial No. 40,291

4 Claims. (Cl. 188—78)

This invention relates to brakes, and is illustrated as embodied in internal expanding automobile brakes of the shiftable anchorage type.

An object of the invention is to provide novel and improved positioning means for the brake shoes or their equivalents. This means is intended to be carried by the backing plate of the brake, and preferably includes a novel adjustable stop for one of the shoes, shown as including a fixed pin engaging the shoe web at its end and carrying a roller engaging the shoe rim. Means may be provided for turning the roller eccentrically on the pin to adjust it, for example a pinion or the like operable from outside the brake. Other objects and features, including various novel combinations of parts and desirable particular constructions, will be apparent from the following description of the illustrative embodiments shown in the accompanying drawing, in which:

Figure 1 is a partial sectional view vertically through the brake, just inside the head of the brake drum, and showing the shoes in side elevation;

Figure 2 is a partial section on the line 2—2 of Figure 1, showing the adjusting means of this brake;

Figure 3 is a partial radial section therethrough, on the line 3—3 of Figure 1; and

Figures 4 and 5 are partial sections, on the lines 4—4 and 5—5, showing the adjustable stop of my improved shoe-positioning means.

In the brake illustrated, shoes 24 and 26 are associated with a drum 21 and a backing plate 22 as described in my Patent No. 2,044,990, granted June 23, 1936. The particular drum shown in the drawing is covered by my Patent No. 2,057,725, granted October 20, 1936.

In this brake, the shoes have at their lower ends sockets 108 formed by registering grooves in stampings 110 spot-welded or otherwise secured to the webs of the shoes. Stampings 110 also carry transverse pivots 142 having central threaded openings adjustably receiving oppositely-extruded right-and-left threaded stems formed on an adjusting member 114.

Member 114 is shown centrally formed with a worm wheel 116 meshing with and driven by a worm formed on a cross shaft 118, floating with the above-described adjustable joint, and the end of which extends outside the backing plate and is there formed to be grasped by a wrench. Shaft 118 is journaled in two end plates 120, slotted to be mounted on the reduced-diameter 55 ends of the pivots 112 and held by a clamp bolt

122 (Figure 3) and spacer sleeve 124 mounted thereon between the end plates.

Shaft 118 is yieldingly held in place by a spring 126, confined between the outer end plate 120 and a snap-ring in the end of the shaft, the spring 5 urging the shaft upwardly in Figure 4 until a snap-ring 128 carried by the shaft engages the second end plate 120. The shaft 118 also carries a washer 130 covering an enlarged opening in the backing plate through which the shaft projects.

Pivots 142 are formed with reduced-diameter ends slidingly engaging the backing plate.

The brake also includes a shoe-positioning device shown in detail in Figures 4 and 5. This device includes a cam-shaped or eccentric-edged roller 144 engaging the inner face of the shoe rim, and having welded or otherwise secured thereto the hub of a stamping 146 having a base engaging the backing plate. The roller 144, with the 20 attached operating member 146, is sleeved on a pin 148 riveted to the backing plate and having its end in supporting engagement with the side of the shoe web. A spring 150 is compressed between roller 144 and a snap-ring 145 in the end of pin 25 148.

The base of member 146 is formed with teeth meshing with the teeth of a small pinion 152 formed or mounted on an operating shaft 154 extending through the backing plate and formed to 30 be grasped by a wrench or the like. A spring 156 sleeved on the shaft 154 is compressed between a snap-ring 155 on the shaft and a locking washer 158 keyed on the shaft. Washer 158 is formed with an annular series of openings yieldingly engageable, against the resistance of spring 156, with a locking projection 160 carried by the backing plate.

While two illustrative embodiments have been described in detail, it is not my intention to limit 40 the scope of my invention to those particular embodiments, or otherwise than by the terms of the appended claims.

I claim:

1. A brake positioning device adapted to be 45 mounted on a brake backing plate and comprising a fixed pin to be carried by the plate and adapted to engage and support at its end the web of a brake shoe, a roller eccentrically mounted on the pin and adapted to engage and support the 50 rim of said shoe, and a device for turning the roller including a pinion having an operating stem extending through the backing plate.

2. A brake positioning device comprising a pin, a roller sleeved on the pin, a spacer secured to the 55

roller and having a hub sleeved on the pin, and a spring engaging the roller and urging the roller and spacer yieldingly to a position determined by the spacer.

3. A brake positioning device comprising an eccentrically-pivoted roller having secured thereto a base spaced from said roller and formed with teeth in its periphery, and an operating member having teeth meshing with the teeth of said base.

4. A brake positioning device comprising an eccentrically-pivoted roller having secured thereto a base spaced from said roller and formed with teeth in its periphery, an operating member having teeth meshing with the teeth of said base, and a yielding locking device for the operating member.

LUDGER E. LA BRIE.
